UNITED STATES PATENT OFFICE.

SEBASTIAN ZIANI DE FERRANTI, OF LONDON, ENGLAND.

COMPRESSION OF ELASTIC FLUIDS.

No. 832,783.

Specification of Letters Patent.

Patented Oct. 9, 1906.

Application filed October 19, 1903. Serial No. 177,703.

To all whom it may concern:

Be it known that I, SEBASTIAN ZIANI DE FERRANTI, a subject of the King of Great Britain and Ireland, and a resident of 31 5 Lyndhurst road, Hampstead, London, N. W., England; have invented certain new and useful Improvements in and Relating to the Compression of Elastic Fluids, (for which I have made application in Great Britain, No. 22,846, bearing date of October 20, 1902,) of which the following is a specification.

My invention relates to elastic-fluid compressors, and especially such as are adapted for attaining high-compression pressures.

15 The compression plants at present known are of three types: first, single or multiple stage piston compressors; second, multiple fan or turbine type compressors, and, third, compressors employing the energy of a 20 volume of water falling under gravity to entrain and compress the elastic fluid. In all compressors of the first type by means of which pressures of one hundred pounds per square inch and upward can be obtained with a 25 moderately high efficiency the bulk and complexity of the apparatus are great, as is also the cost. Again, with compressors of the second type it is owing to the difficulties which occur practically impossible to attain 30 efficiently pressures of one hundred pounds and upward, while the third type of compressor has only been employed hitherto to effect compression by means of water falling under gravity, as occurs in the case of the 35 utilization of a waterfall for the purpose of compression. High pressures can only be obtained with such an arrangement at very great expense; and the proportion of water to air has hitherto always been too great to 40 enable high efficiencies to be attained.

Now my invention has for its object to render possible the attainment of very high compression pressures in a simple and efficient manner—that is, directly from a rotary motion without reciprocating parts.

45 My invention consists in the features and combination and arrangement of parts hereinafter described, and particularly pointed out in the claims.

50 My invention in all cases comprises a rotary or centrifugal pump or circulator, means for effecting the entrainment of elastic fluid with the liquid, means for cooling the circulated liquid which is the medium of compression, so that the compression may be practically isothermal, and means for separating

the liquid from the elastic fluid, said liquid being either used again in the cycle to conserve the energy it contains or being rejected by way of a motor whose work is added to that of the system.

A compressor, according to one form of my invention adapted to compress air, consists of tubes, into which liquid under pressure is shot intermittently at high velocity, 65 so as to form a number of liquid traveling pistons with volumes of air intervening, so that as the pistons of liquid move along they give up their kinetic energy in compressing the air. The tubes feed into a separate 70 chamber, from which the air is collected, and the liquid is returned under pressure to the centrifugal pump or rotary part, which again gets up the necessary velocity for the liquid-pistons. The tubes may be arranged as a 75 ring to receive liquid shot out radially or at some suitable angle to the radii of the centrifugal or rotary thrower, or the liquid may be supplied through oscillating jets or their equivalents, the jets being adapted to oscillate between tubes, so that air is entrained.

My invention contemplates providing for the discharge of the liquid into the separating-chamber at a velocity as nearly zero as possible or for utilizing such velocity as it 85 possesses to supply power to aid in the compression, so that the energy it represents may not be lost.

Referring to the accompanying drawings, Figures 1 and 2 are side elevations and plan, 90 respectively, of a form of compressor having a centrifugal thrower and working in a closed cycle, Fig. 3 being a corresponding end view. Fig. 4 shows a modified form of the above in which the pressure energy of the compressing liquid is utilized in driving a suitable turbine or the like, while Fig. 5 shows a similar arrangement working in an "open" cycle. Fig. 6 shows in sectional elevation a general arrangement of apparatus embodying 95 a thrower of the nature shown in the above drawings and driven electrically. Fig. 7 is an elevation, partly in section, of another arrangement of parts, Fig. 8 being a detail view of the rotating nozzle employed, while 100 Fig. 9 shows a modification in which an oscillating nozzle is used.

The drawings being of a diagrammatic nature merely, I do not confine myself in any way to the precise proportions or details of 105 parts shown therein.

In constructing a rotary air-compressor

according to one form, as shown in Figs. 1, 2, and 3, suitable for working in a closed cycle I provide a number of fixed tubes *a* in a ring, with their inlets disposed toward the center. 5 Within the ring of inlets I rotate a jet centrifugal pump or liquid-thrower *b*. This pump comprises a central admission for liquid (shown in Fig. 1 as supplied through the nozzle *c*) and one or more circumferential discharge-nozzles *d*, arranged so that the liquid discharges around the ring of inlet-orifices of the fixed air-compression tubes *a* at a high velocity and intermittently. Non-return valves may be arranged, if necessary, 10 in any suitable position on the compression-tubes. The central centrifugal thrower *b* is rotated at a high velocity and the nozzles *d* are so placed that air-supply passages *e* intervene between the liquid-jets. The effect of 15 rotating the centrifugal thrower is therefore to discharge into the fixed ring of pipes alternate liquid-pistons and air-plugs to be compressed, the nozzles being arranged at suitable angles with the tubes to avoid shock. 20 The liquid discharges along each compressing-tube *a* with great velocity, compressing the air before it into one or more separating-chambers *f*, arranged, preferably, circumferentially, and at the same time loses 25 the greater part of its velocity. I so shape the compressing-tubes *a* by gradually enlarging their cross-sections as to favor this reduction of velocity as much as possible. The compressing liquid and air pass together. 30 out of the separating-chambers *ff* by way of the pipes *h h* into the additional separator *i*, in which the baffle plates or trays *k k* complete the separation. When convenient, the separation of the liquid and air may be 35 accomplished in a single separator of suitable dimensions. To obtain high efficiencies, it is essential to make use of the energy of the liquid under pressure in the separating-chamber. This may be conveniently accom- 40 plished, as shown in Figs. 1, 2, and 3, by causing the liquid to return to the centrifugal thrower by way of the pipes *l l* and contracting nozzle *c*, the liquid in this manner ac- 45 quirring a high velocity. A suitable cooler 50 *m* is interposed in the line of pipes *l l*, the circulating-water service-pipes for the cooler being shown at *n n*. The air compressed is led away from the separating-chamber *i* by 55 way of the pipe *o*. To provide room for the enlarged ends of the compressing-tubes where they enter the first separating-chamber, they may be arranged in a zigzag or "staggered" manner, the separating-chamber being divided, if necessary, into two 60 parts, as shown, arranged one on each side of the centrifugal thrower, the compressing-tubes then preferably leading alternately to each of the two chambers.

In order to insure substantially isothermal 65 compression of the air, I prefer to humidify

it and may for this purpose use a device, for example, such as is shown in Fig. 8, though any known apparatus fulfilling the required function may be utilized. Referring to Fig. 8, a hollow ring 18, connected to a water-supply by the pipe 19, is provided with a number of nozzles 20, passing through the casing 10 and projecting radially into the space through which the air to be compressed passes. A second ring 21, connected to the compressed-air reservoir through the pipe 22, is arranged within the casing 10, as shown. From this ring 21 other nozzles 23 project equal in number to the nozzles 20 and so arranged as to project jets of air across the mouths of the nozzles 20. By this means the issuing jets of water are thoroughly atomized and the air to be compressed is charged with a fine aqueous spray or mist.

I prefer to so arrange the inlet and discharge passages of the liquid thrower that the pressure of the liquid is at or below atmospheric pressure at the points where the fixed and rotary parts of the apparatus meet, so that packed joints may be unnecessary. 85

The area of the pipe *l* at the point where it contracts to supply the thrower *b* with liquid may be so reduced as to entrain any desired proportion of the total quantity of air compressed. In this case part or all of the 90 air passes through the thrower and enters the compressing-tubes with the liquid. As the air-spaces *e* in such an arrangement become wholly or in part unnecessary, additional nozzles similar to *b* may be arranged 100 on the thrower.

Another method of working in a closed cycle is shown in Fig. 4, in which the same letters are used as in the previous figures to denote corresponding parts. The pressure 105 energy of the liquid in the separator is in this case utilized by driving the Pelton wheel or the like *r*, the liquid being led from the separator through the pipe *s*. The Pelton wheel, which is conveniently mounted on the same 110 shaft as the driving-motor *t* and thrower *b*, but which may be connected by any suitable gearing, thus usefully employs the pressure 115 energy of the liquid. The exhaust from the Pelton wheel is led away by the pipe *u* to a cooling-pond or other cooler, the liquid being finally returned to the thrower through the pipe *v*.

Fig. 5 shows an arrangement of parts similar to that in Fig. 4, but adapted for use with 120 an open cycle. The exhaust liquid from the Pelton wheel is in this case thrown away by way of the pipe *u*, fresh liquid being supplied to the thrower through the pipe *v*.

In both of the arrangements shown in Figs. 125 4 and 5 if the liquid is supplied to the thrower *b* under a head due either to gravity or a pump the supply-pipe *v* is preferably of a contracting cross-section where it discharges into the thrower, so that the pressure may be 130

reduced at this point to atmospheric pressure, or thereabout, and thus render packed joints unnecessary. If there is no head, however, a suitable form of gland must be adopted.

5 In Fig. 6 I have shown a general arrangement of apparatus with the centrifugal-thrower spindle *w* arranged vertically, an electric motor *x* being conveniently mounted on a prolongation of this spindle. The compressing-tubes *a* deliver into the separator-chamber *z* and may be arranged, as shown, to pass through the jacket 2, surrounding this chamber, the cooling-water in this jacket being constantly renewed in any convenient 10 manner in order to prevent rise of temperature during compression. The compressed air passes from the separator-chamber by way of the pipe 3. I may allow the discharging-jets as they discharge from the 15 compression-tubes *a* to impinge upon an impact wheel or turbine 4, so as to cause rotation, and this power I may utilize, as shown, for instance, in Fig. 6, to aid in driving the 20 centrifugal pump or thrower. The turbine itself in this case also acts as an efficient means of separating the air and liquid. The liquid passes from the separator-chamber *z* back to the pump and is used over again to 25 compress a further quantity of air. The power for driving the rotary liquid-piston air-compressor may be supplied from any 30 convenient motor. By this part of the invention I am enabled to produce a liquid-piston compressing-pump capable of compressing air isothermally, the dimensions being very small for a great power. It is to be 35 understood that in all cases I use a separating-chamber for separating the liquid and compressed air, and where I desire very high 40 pressures I may utilize a series of rotary compressors, each one discharging its air into the next.

In carrying out another part of my invention according to one form I provide a number of fixed tubes 5, as before, into which I discharge (see Figs. 7 and 8) liquid at considerable velocity by means of a rotating piece carrying a suitable number of nozzles 9, rotating within a casing 10. The revolving 45 nozzles may be driven in any convenient manner—as, for instance, by a belt engaging with the pulley 11, or the nozzles themselves may be inclined, so as to assist the rotation by reaction. A series of liquid pistons is 50 thus discharged into the tubes, which may be either parallel or expanding, according to the quantity of air entrained, the tubes 5 delivering into a separating-chamber 12, whence the liquid passes to a centrifugal pump or 55 liquid thrower 13 to have its velocity restored to it. The liquid then returns by way of the pipe 14 to the rotating nozzles, thus completing the cycle. A cooler 15 is arranged at 60 any convenient point in the circuit to prevent undue rise of temperature of the com-

pressing liquid. Instead of employing a rotating nozzle I may, as shown in Fig. 9, use a nozzle 16, adapted to receive an oscillating motion from any suitable gearing, such as 17. The nozzle will then pass to and fro across 70 the ends of the compressing-tubes 5, causing alternate pistons or plugs of air and water to pass down the tubes, as in the last form described. The other reference-letters on Fig. 9 bear the same significance as in Fig. 7 75 above.

In all cases the compression-tubes must be arranged of such length as to contain a sufficient number of liquid pistons to preclude any possibility of air and liquid blowing back 80 from the separating-chamber.

It is to be clearly understood that in all these modifications of my invention multiple-stage compression may be adopted when it is desired to obtain air at a very high pressure, and in all cases the liquid circulated is 85 thoroughly cooled between the stages as well as in the ordinary course.

Where a separate centrifugal pump is used to give energy to the cycle, it may be placed 90 so as to deal either with the liquid or mixture.

My invention is applicable to the production of compressed air or compressed gas of any kind for any purpose, and mercury, oils, 95 water, or any other suitable liquids may be employed as the medium of compression.

Having now described my invention, what I claim as new, and desire to secure by Letters Patent, is—

1. An elastic-fluid compressor employing a liquid as the medium of compression, comprising means for giving the liquid velocity, a plurality of fixed tubes or ducts receiving the liquid from such means through which 105 the elastic fluid is compressed successively under pressure by said liquid and a means with which said tubes connect for receiving the discharge therefrom.

2. An elastic-fluid compressor employing 110 a liquid as the medium of compression comprising a tube, means for intermittently discharging said liquid thereinto and positively cutting it off therefrom to form separate liquid traveling pistons to entrain and compress the elastic fluid in the form of independent plugs and means for receiving the compressed fluid.

3. An elastic-fluid compressor employing 115 a liquid as the means of compression, comprising a plurality of fixed tubes or ducts having open ends and means passing over said open ends for discharging a high-velocity stream of liquid successively into said open ends, so as to entrain the elastic fluid in the 120 form of independent plugs.

4. An elastic-fluid compressor employing 125 a liquid as the medium of compression, comprising a plurality of tubes or ducts having open ends separated by sharp edges, and 130

means passing over said open ends for discharging a high-velocity stream of liquid successively into said open ends so as to entrain the elastic fluid in the form of independent 5 plugs.

5. An elastic-fluid compressor employing a liquid as the medium of compression, comprising a plurality of tubes or ducts having open ends, means for producing one or more 10 high-velocity streams of liquid and means for causing relative motion between said streams and said open ends presented to them, so as to entrain in said tubes the elastic fluid in the form of independent plugs.

15. In elastic-fluid compressors employing liquid as the compressing medium, compression tubes or ducts, means for producing one or more high-velocity streams of liquid and for supplying the said liquid to each tube by 20 a succession of feeding actions to form separate liquid traveling pistons and means for receiving the discharge of said tubes, said tubes having their cross-sectional areas enlarged toward the said receiving means.

25. In combination with a chamber, a plurality of fixed ducts or tubes leading thereto and movable means for discharging liquid successively to the said tubes to form liquid traveling pistons therein and to entrain elastic fluid for compression.

30. In combination with a chamber, a plurality of fixed ducts or tubes leading thereto and straight in the neighborhood of their inlet ends and movable means for discharging liquid successively to the said tubes to form liquid traveling pistons therein and to entrain elastic fluid for compression.

35. In combination with a chamber, a plurality of fixed ducts or tubes leading thereto and straight in the neighborhood of their inlet ends, said straight portions having their cross-sectional areas enlarged toward said chamber and movable means for discharging liquid successively to the said tubes to form 40 liquid traveling pistons therein and to entrain elastic fluid for compression.

45. In combination with a chamber, a plurality of ducts or tubes leading thereto and movable means for discharging liquid successively to the said tubes to form liquid traveling pistons therein and to entrain elastic fluid for compression, the axial direction of the inlet ends of said tubes corresponding to the path in space which would be taken by the particles of liquid shot freely from said discharge means.

50. In combination with a chamber, a plurality of ducts or tubes leading thereto and movable means having one or more discharge

55. orifices for discharging liquid successively to the said tubes to form liquid traveling pistons therein and to entrain elastic fluid for compression, said discharge-orifices being each of area sufficient to cover a plurality of the inlet-openings of said tubes.

60. 12. In combination with a chamber, a plurality of fixed ducts or tubes leading thereto and movable means working with charges composed wholly of liquid for discharging same successively to each of the said tubes to 65 form liquid traveling pistons therein and to entrain elastic fluid for compression.

65. 13. An elastic-fluid compressor employing a liquid as the medium of compression, comprising means for giving the necessary velocity to the liquid, a chamber and means for dividing the liquid into separate liquid traveling pistons interposed between the chamber and the said velocity-producing means, ducts 70 between said dividing means and the chamber, said dividing means comprising a movable part.

75. 14. An elastic-fluid compressor employing a liquid as the medium of compression, comprising in combination one or more rotatable 80 ducts, fixed tubes into which liquid passes from said ducts thereby entraining elastic fluid, a fixed separating-chamber into which said tubes discharge, cooling means for the compressing liquid and a contracting nozzle 85 through which said compressing liquid passes to said rotatable ducts.

85. 15. An elastic fluid-compressor employing a liquid as the medium of compression comprising a plurality of tubes or ducts having 90 open ends, means for producing one or more high-velocity streams of liquid, means for causing relative motion between said streams and said open ends presented to them, so as to entrain in said tubes the elastic fluid in the form of independent plugs, together with 95 means for humidifying said elastic fluid so as to keep down the temperature during compression.

100. 16. In elastic-fluid compressors employing liquid as the medium of compression, a movable element for throwing separated pistons of liquid and a fixed nozzle at the admission of the said movable element converging sufficiently to reduce pressure to about atmospheric, substantially as described.

105. In witness whereof I have hereunto set my hand in presence of two witnesses.

SEBASTIAN ZIANI DE FERRANTI.
